IRONING MACHINE

Edward J. Frey, Dayton, Ohio, assignor to General Motors Corporation, Detroit, Mich., a corporation of Delaware

Application July 1, 1954, Serial No. 440,590

17 Claims. (Cl. 38—60)

This invention relates to a domestic appliance and more particularly to domestic ironing machines.

Domestic ironing machines are very practical and save time and effort for flat work. They have not been very practical for clothing because the ironing of clothing is too intricate for the large immobile rectangular shoe ordinarily provided.

It is an object of my invention to provide a practical arrangement for ironing clothes as well as flat work upon a domestic ironing machine.

It is another object of my invention to provide an arrangement wherein a small mobile pointed auxiliary shoe can be located forwardly of the main shoe in cooperative relation with the ironing roll.

It is an other object of my invention to provide an arrangement wherein pressure can be applied from the power element of the ironing machine to a small auxiliary shoe in such an arrangement that the small auxiliary shoe can be moved laterally at will within reasonable limits.

It is an other object of my invention to provide an arrangement wherein pressure can be applied from the power element of a machine to a small mobile auxiliary shoe in such an arrangement that the small auxiliary shoe can be readily moved away from the main shoe to provide unimpeded use of the main shoe.

These and other objects are attained in the forms of the inventions shown in the drawings. The conventional shoe operating shaft is provided with a two-position spring linkage with the supporting arm for the main shoe. The main shoe is provided with a resilient supporting arrangement to which is pivotally connected the two supporting arms for the small auxiliary shoe. The auxiliary shoe is slidably mounted upon a pair of rods extending between the pivoted supporting arms so that it may be moved laterally while in engagement with the ironing roll. The two supporting arms are provided with a latching arrangement to the resilient supporting arrangement providing a resilient connection with the main shoe. The double linkage and the latching and unlatching supporting arrangement for the auxiliary shoe allow the auxiliary shoe to be latched into position forwardly of the main shoe with the auxiliary shoe adapted to contact the roll while the main shoe is held away from the roll. The pressure applying means for the main shoe is used to apply the pressure through the main shoe and the resilient support to the small auxiliary shoe. Whenever desired the supporting arms for the auxiliary shoe may be unlatched from the resilient supporting arrangement on the main shoe and the spring linkage changed to bring the main shoe into contact with the roll while the auxiliary shoe is moved away from the roll to permit unimpeded use of the main shoe for flat work.

Further objects and advantages of the present invention will be apparent from the following description, reference being had to the accompanying drawings wherein a preferred form of the invention is clearly shown.

In the drawings:

2

Figure 1 is a front view of an ironing machine embodying one form of my invention;

Figure 2 is an end view of the upper portion of the ironing machine shown in Figure 1 with the auxiliary shoe out of operating position and the main shoe in contact with the roll;

Figure 3 is a view similar to Figure 2 but with the auxiliary shoe in contact with the roll and the main shoe away from the roll;

Figure 4 is a top view of the auxiliary shoe and its supporting arrangement as shown in Figure 3;

Figure 5 is a fragmentary sectional view taken along the line 5—5 of Figure 3;

Figure 6 is a fragmentary elevational view similar to Figures 2 and 3 showing the unlatching of the spring linkage between an operating arm on the shoe operating shaft and the shoe supporting arm for the main shoe;

Figure 7 is a vertical sectional view through the auxiliary shoe taken along the line 7—7 of Figure 4;

Figure 8 is a wiring diagram of the driving motor and heating elements and the controls;

Figure 9 is a fragmentary top view of an ironer showing a modified form of the invention;

Figure 10 is a dial for the temperature adjustment knob upon the auxiliary shoe shown in Figure 9;

Figure 11 is an end view of an ironer with the modified construction;

Figure 12 is a sectional view taken along the line 12—12 of Figure 11;

Figure 13 is a fragmentary sectional view taken along the line 13—13 of Figure 12; and

Figure 14 is a fragmentary sectional view taken along the line 14—14 of Figure 11.

Referring now to the drawings and more particularly to Figure 1 the ironing machine includes a bed plate 20 of rectangular shape and plan provided with the supports 22 and 24 at opposite ends. These supports 22 and 24 are provided with suitable supporting rollers 26 at their lower ends. The bed plate may be provided with drop

40 leaves 28 at the sides and front which may be lifted to horizontal positions to extend its working surface. At one end the bed plate 20 is provided with a gear housing 30. This gear housing is provided with a motor switch 32, a heat switch 34, a control lever 36 and a pilot light 38. The gearing within the housing 30 is connected in driving relationship to a roll shaft on which is mounted the padded ironing roll 40. Also extending from the gear housing 30 through a supporting sleeve 42 is the shoe operating shaft 44. This may be controlled by the lever 36 or through the foot treads 46 and 48 which may be connected to the mechanism within the gear housing 30 by one or more rods 50. The driving motor and the gearing connecting the driving motor with the roll shaft and roll 40 as well as the mechanism connecting the motor with the shoe operating shaft 44 may be of the type shown in one or more of the Janda Patents 1,867,839, 2,026,345 and 2,054,631.

The ironing machine is provided with a main ironing shoe 52 adapted to contact the rear side of the roll as shown in Figure 2 and extending along the major portion of the roll 40 as illustrated in Figure 1. The main ironing shoe is pivotally connected by a pivot pin 54 to a pair of spaced supporting links 56 which are pivotally mounted upon the shoe operating shaft 44. The shoe operating shaft 44 has fixed to it the shoe operating arm 58. The shoe operating arm 58 is forked and at its upper end carries inwardly turned projections or rollers 60. Pivotally connected to the spaced shoe supporting links 56 upon the pin 62 is a block 64 through which extends the rod 66 of a spring link. The one end of this rod 66 is shaped in the form of two spools 68 and 70 which form clutching or latching grooves in combination with the inturned

60 of the roll 40 as illustrated in Figure 1. The main ironing shoe is pivotally connected by a pivot pin 54 to a pair of spaced supporting links 56 which are pivotally mounted upon the shoe operating shaft 44. The shoe operating shaft 44 has fixed to it the shoe operating arm 58. The shoe operating arm 58 is forked and at its upper end carries inwardly turned projections or rollers 60. Pivotally connected to the spaced shoe supporting links 56 upon the pin 62 is a block 64 through which extends the rod 66 of a spring link. The one end of this rod 66 is shaped in the form of two spools 68 and 70 which form clutching or latching grooves in combination with the inturned

65 of the roll 40 as illustrated in Figure 1. The main ironing shoe is pivotally connected by a pivot pin 54 to a pair of spaced supporting links 56 which are pivotally mounted upon the shoe operating shaft 44. The shoe operating shaft 44 has fixed to it the shoe operating arm 58. The shoe operating arm 58 is forked and at its upper end carries inwardly turned projections or rollers 60. Pivotally connected to the spaced shoe supporting links 56 upon the pin 62 is a block 64 through which extends the rod 66 of a spring link. The one end of this rod 66 is shaped in the form of two spools 68 and 70 which form clutching or latching grooves in combination with the inturned

projection or roller 60. The opposite end of this rod 66 is surrounded by a heavy type coil spring 72 which is confined between the block 64 and the spring retainer 74 which is adjustably threaded onto the end of the rod 66.

Connected to the block 64 is the release handle and arm 76 which is sufficiently long to extend well above the main shoe 52. When this release lever 76 is moved rearwardly to the position shown in Figure 6, the spring-link arrangement is tilted so that either of the spool shaped portions 68 or 70 can be moved into engagement with the end portion 60 of the shoe operating arm 58 as shown in Figures 3 and 2. When the end portion 60 is in engagement with the spool shaped portion 68 as shown in Figure 3 the shoe 52 is held away from the roll 40 as shown in Figure 3. When the end portion 60 is in engagement with the spool portion 70, the shoe operating arm may be moved to bring the main shoe 52 in engagement with the roll 40 as shown in Figure 2. The usefulness of such an arrangement will be shown in connection with the use and operation of the auxiliary shoe and the main shoe.

Upon the upper edge of the main shoe are fastened two spaced yielding bracket structures 78. These bracket structures include a flexible tongue 80 fastened to the upper lip of the sole plate of the main shoe 52. Each of the bracket structures 78 also has an end portion 82 which is supported and reinforced by the compression coil spring 84 which is supported on a bracket 86 fastened to the back of the main shoe 52. Each of the bracket structures 78 is provided with a curved edge portion 88 leading to a latching notch 90. Each of the bracket structures 78 carries a pivoting rod 92 to which is connected at either end the supporting arms 94 and 96. Each of the supporting arms 94 and 96 is provided with a longitudinal slot 98 in which there is slidably mounted a latching rod 121. This latching rod 121 is normally held in the position shown in Figures 2 and 3 by the coil springs 123.

The supporting arms 94 and 96 also are spanned by the guide rods 125 and 127 which may be fastened by the screws 129. The small auxiliary shoe 131 is provided with the bearings 133 and 135 which are slidably mounted upon the rod 127. Preferably these bearings 133 and 135 are a form of ball bearing which includes a plurality of raceways having balls 137 in one portion of the track in rolling contact with the guide rod 127 and the projection 139 upon the wall of the bearing 135 while the return portion of the raceway contains the balls 141 which are held out of contact with the guide rod 137 by the raceway support 143.

The auxiliary shoe 131 is provided with a sole plate 145 upon which is mounted a sheathed tubular type of electric heater 147 held in place by the clamping plate 149 and the screws 151 which thread into the sole plate 145. The sole plate 145 has a concave cylindrical surface adapted to fit the ironing roll 40. The auxiliary shoe 131 also is provided with a cover 153 which encloses the heating element 147 and provides a platform on which the bearings 133 and 135 are mounted and fastened by the screws 155. Also fastened to the top of the cover 153 is an adjustable thermostat for the shoe 131 and a handle 157 terminating in a knob 159. The handle 157 may be moved to the right or left in order to move the auxiliary shoe to the right or to the left either when the roll 40 is turning or when it is stopped.

Extending above the shoe 131 over the guide rod 127 is a bracket 161 having a spring arm 163 fastened thereto and extending rearwardly therefrom. This spring arm 163 extends in engagement with the top flange of a channel member 165 fastened to the supporting arms 94 and 96. This channel 165 limits the movement of the spring arm and the shoe 131 about the axis of the guide rod 127 without limiting the axial movement in any way.

As shown in Figure 2 the auxiliary shoe 131 and the supporting arms 94 and 96 and the parts connected thereto may be pivoted upwardly upon the axis of the rod

92 until the supporting rod engages the rear portion 82 of the resiliently mounted supports 78. The tension coil spring 167 through its connection with the forward end of the link rod 66 normally holds the spool shaped portions 68 or 70 in engagement with the roller end portion of the shoe operating arm 58. In Figure 2 the shoe operating rod 44 exerts a force through the arm 56, the roller 68 and the spool shaped notch member 70, the rod 66, the spring retainer 74 and the spring 72 upon the block 64 which through the pivot pin 62 acts through the supporting arms 56 to apply the sole plate of the main shoe 52 to the roll 40. With the auxiliary shoe 131 lifted up in the manner shown in Figure 2 the main shoe may be used for flat work without being impeded in any way by the auxiliary shoe 131 and its associated mechanism.

When it is desired to use the auxiliary shoe 131 the release handle 76 is moved to the rear as shown by the dot-dash arrow in Figure 2 to the position shown in Figure 6 to release the spool shaped notch 70 from the roller 60. The handle 159 is then pulled downwardly until the curved edge 88 upon the supports 78 cams the rod 121 outwardly until it drops into the notch 90 to latch the support arms 94 and 96 to the supports 78. This brings the auxiliary shoe to the position shown in Figure 3 on top of the roll 40 forwardly of the leading edge of the main shoe 52.

In this position the operating shaft 44 through the mechanism in the gear housing 30 may receive a counter-clockwise turning force to move the arm 58 and the link rod 66 to the left to compress the spring 72 and apply a force to the supporting arms 56. This force will be transmitted through the main shoe 52 and the support 78 and the springs 84 to the supporting arms 94 and 96 and the rod 127 through the bearings 133 and 135 to the shoe 131 for applying the ironing pressure. This auxiliary shoe 131 then may be moved to the left or to the right either while the roll 40 is turning fast or slow or is stopped under the control of either the pedal 46 or the handle 36.

The auxiliary shoe 131 has its heater element 147 connected to the power supply by the electrical conductors 169 and 172 under the control of the adjustable thermostat 170. The heating circuit may be arranged as shown in Figure 8 including the supply conductors 171 and 173. The driving motor 175 is connected by the switches 32 and 179 to the supply conductors 171 and 173. The main shoe is provided with two extensive heating elements 181 and 183 individually controlled by the adjustable thermostats 182 and 184. These heating elements may each extend in heat exchange relation with about 50% of the area of the main shoe and each may be capable of supplying about 50% of the maximum heat permissible. The heater 181 has one conductor 185 connected to the supply conductor 171 and its second conductor 187 connected to the terminal 189 of a double throw double pole heater switch 34. The other corresponding terminal 193 of the double pole double throw heater switch 34 is connected to one of the conductors 169 connecting to one terminal of the heater 147 of the auxiliary shoe 131. The other terminal of the heater 147 connects through the adjustable thermostat 170 and the conductor 172 to the supply conductor 171. The movable switch blades of the double throw heater switch 34 are both connected to the supply conductor 173. The terminal 189 of the double throw heater switch 34 is also connected to the opposite terminal 195 by the conductor 197. The terminal 195 is also connected to the pilot light 38 which is also connected to the supply conductor 171. The remaining terminal 191 of the double throw switch 191 is connected to one terminal of the heating unit 183 while the other terminal of the heating unit 183

is connected by the conductor 177 to the supply conductor 171.

With this wiring arrangement, when the double throw heater switch 34 is moved to make connection with the contacts or terminals 189 and 193 the heating units 147 and 181 are connected in parallel circuit relationship to the supply conductors 171 and 173 while the heating unit 183 is disconnected. When the double throw double pole heater switch 34 is moved to connect to the contacts and terminals 195 and 191, the heating units 181 and 183 are connected in parallel to the supply conductors 171 and 173 while the heating unit 147 is disconnected. This arrangement makes it possible to keep the main shoe 52 relatively warm and ready for use while the auxiliary shoe 131 is being used, since during the use of the auxiliary shoe the heater 181 supplies heat to the main shoe 52.

In Figures 9 to 14 a modified form of the invention is shown in which the operating handle for the pivoted arm is pivotally connected to the upper edge of the main shoe in such a way that pressure can be applied through the arm to the auxiliary shoe. The auxiliary shoe is provided with a universal type joint connection with the arm so that its concave cylindrical surface may always be in proper coaxial alignment when it is in engagement with the roll 40. When not in use the auxiliary shoe is pivoted back to a position over and behind the main shoe.

In the modification shown in Figures 9 to 14 the ironing shoe 52 and the ironing roll 40 are the same as shown in Figures 1 to 8 and are operated by the same mechanism. The difference between the two modifications lies in the different supporting arrangement for the auxiliary shoe. In the modified form there is provided an auxiliary shoe 220 having a substantially four-sided shape with a curved edge 222 on its front side which is also considerably longer than the rear side. This forms the pointed ends 224 and 226 which are especially useful in ironing clothing. The auxiliary shoe 222 is also provided with a temperature adjusting knob 228 which is connected to a temperature adjusting device within the shoe 220 whereby its temperature may be limited in the same manner as can the temperature be controlled in a conventional hand iron. This knob is shown enlarged in Figure 10 and bears legends indicating the temperatures suitable for different fabrics.

As in the previous modification the auxiliary shoe 220 is located forwardly of the main shoe and can be swung out of this position to a position over the main shoe when it is not desired to use the auxiliary shoe. The difference between the two is that in this latter modification, the swinging is done about a vertical axis which results in a more simple mechanical arrangement whereas in the first modification, the auxiliary shoe is swung out of use on a horizontal axis.

The auxiliary shoe 220 is provided with a pivot pin 230 which provides a pivotal connection with a U-shaped member 232. This U-shaped member 232 is connected by the pivot pin 234 to the ears 236 extending downwardly from the flat spring arm 238. This flat spring arm 238 is depressed downwardly in front of the roll 40 and provided with a suitable operating knob 240 at its front end in a location very similar to that of the first modification.

The rear end of the spring arm 238 is forked and provides spaced bearings upon a pivot pin 244. The pivot pin 244 is mounted in a pivot member 246 provided with upper and lower bearings 248 and 250 which are rotatably mounted upon the fixed vertical pivot pin 252. This fixed vertical pivot pin 252 is fixed to a supporting block 254 fastened to the upper edge of the main shoe 52 as shown best in Figure 11. This pivot member 246 is provided with a spring pressed pin 256 adapted to engage the arcuate slot 258 provided with vertical shoulders at both ends which limit the rotation of the pivot member 246 to about 180°. The rearmost portion of the slot 258

is provided with a depression 260 for yieldingly holding the auxiliary shoe and the arm 238 in the dot and dash line position shown in Figure 9.

Within the pivoted member 246 there is provided a flat leaf spring 262 fastened at its front end by the clamping projections 264 to the bottom side of the arm 238. This flat spring extends over the pivot pin 244 and thence downwardly and has its lower end resting against the vertical pivot pin 252. This flat spring 262 exerts an upward force tending to lift the auxiliary shoe a limited distance when no downward force is manually applied to the knob 240. In order that the auxiliary shoe 220 at all times remains parallel to the axis of the ironing roll 40, it has its rear right hand corner provided with a loose pivotal connection 266 with a link 268 extending rearwardly. This link 268 has a downwardly extending portion 270 connected by the pivot pin 272 to an arm 274 extending from the support 254. The arm 274 together with the arms 238 and 268 and pivotal connections with the auxiliary shoe 220 form a parallelogram which keeps the auxiliary shoe parallel to the axis of the roll 40 at all times. It also serves as a very convenient method of locating the auxiliary shoe 220 in a suitable position when the arm 238 is moved into its dot and dash line position shown in Figure 9.

In this second modification the auxiliary shoe 220 is used in a manner similar to the auxiliary shoe 131 of the first modification. The ironing shoe 52 is moved to its rearmost position in which the inturned projections or rollers 60 are in engagement with the spool shaped portion 68. In this position the shoe operating arm has a controlled movement between the dot and dash line location and the full line location shown in Figure 11. If it is desired to use the auxiliary shoe 220, the main shoe 52 is first moved rearwardly to its dot and dash line position shown in Figure 11. The operating handle 240 is grasped and pulled forwardly from the dot and dash line position shown in Figure 9 to the full line position in which the auxiliary shoe 220 is forward of the main shoe 52. The shoe operating shaft 44 is then moved forward by the power of the electric motor of the ironing machine to the full line position shown in Figure 11 so as to apply ironing pressure between the auxiliary shoe 220 and the roll 40. When in this position the knob 240 may be moved laterally through an angle of nearly 90° so that the auxiliary shoe is moved in the axial direction relative to the ironing roll 40. This makes it possible to iron clothing with the auxiliary shoe 220. The ironing roll 40 can be stopped or rotated either at a slow speed or a high speed. This arrangement makes it possible to iron ruffled dresses, pleated dresses and other clothes that are difficult to iron.

While the form of embodiment of the invention as herein disclosed constitutes a preferred form, it is to be understood that other forms might be adopted as may come within the scope of the claims which follow.

What is claimed is as follows:

1. An ironing machine including an ironing roll, a main ironing shoe extending along the major portion of said roll, an auxiliary shoe located forwardly of the main shoe in front of its leading edge, means for arranging either of said shoes into operative position with said roll, a motor for driving said roll, and means powered by said motor for applying pressure through whichever shoe is in the operative position with the roll.

2. An ironing machine including an ironing roll, a main ironing shoe extending along the major portion of said roll, an auxiliary shoe located forwardly of the main shoe, means for arranging either of said shoes into operative position with said roll, a motor for driving said roll, and means powered by said motor for applying pressure through whichever shoe is in the operative position with the roll, said auxiliary shoe being provided with a pivotal mounting upon the main shoe located at such a position and angle to establish the arc of travel of the auxiliary

shoe about the pivotal mounting from a position in front of the leading edge of the main shoe to a position above the main shoe.

3. An ironing machine including an ironing roll, a main ironing shoe extending along the major portion of said roll, an auxiliary shoe located forwardly of the main shoe, means for arranging either of said shoes into operative position with said roll, a motor for driving said roll, and means powered by said motor for applying pressure with the operative shoe, said auxiliary shoe being provided with a pivotal mounting upon the main shoe located at such a position and angle to establish the arc of travel of the auxiliary shoe about the pivotal mounting from a position in front of the main shoe to a position above the main shoe, said pivotal mounting including an arm pivotally mounted upon the main shoe and a universal type connection between the arm and the auxiliary shoe.

4. An ironing machine including an ironing roll, a main ironing shoe extending along the major portion of the roll, an auxiliary shoe located forwardly of said main shoe and pivotally connected to the main shoe, and latch means located in such a position to releasably lock said pivotal connection in a position to place said auxiliary shoe adjacent said roll while said main shoe is spaced a greater distance from said roll.

5. An ironing machine including an ironing roll, a main ironing shoe extending along the major portion of the roll, an auxiliary shoe located forwardly of said main shoe and having a pivotal connection to the main shoe, and latch means located in such a position to releasably lock said pivotal connection in a position to place said auxiliary shoe adjacent said roll while said main shoe is spaced a greater distance from said roll, said pivotal connection including means forming a laterally movable mounting for said auxiliary shoe.

6. An ironing machine including an ironing roll, a main ironing shoe extending along the major portion of the roll, an auxiliary shoe located forwardly of said main shoe and having a pivotal connection to the main shoe, latch means located in such a position to releasably lock said pivotal connection in a position to place said auxiliary shoe adjacent said roll while said main shoe is spaced a greater distance from said roll, said pivotal connection including means informing a laterally movable mounting for said auxiliary shoe, and a manual operating means for laterally moving said auxiliary shoe upon said mounting.

7. An ironing machine including an ironing roll, a main ironing shoe extending along the major portion of the roll, an auxiliary shoe located forwardly of said main shoe and pivotally connected to the main shoe, said pivotal connection including a latching structure connected to said main shoe and a latching and unlatching connection between said latching structure and said auxiliary shoe and a spring means acting between said latching structure and main shoe for urging said auxiliary shoe in the direction of the roll.

8. An ironing machine including an ironing roll, an ironing shoe adapted to cooperate with said roll, a shoe supporting arm connected to said shoe, a shoe operating shaft, and a release actuator means having means for operatively connecting said shoe operating shaft and said shoe supporting arm in two different angular operating relationships and also having means for releasing the operative connection between said shaft and arm.

9. An ironing machine including an ironing roll, a main ironing shoe extending along the major portion of the roll, a plurality of parallel rods connected to the main shoe, and an auxiliary shoe slidably mounted on said parallel rods for lateral movement relative to the main shoe.

10. An ironing machine including an ironing roll, a main ironing shoe extending along the major portion of the roll, a plurality of parallel rods connected to the

main shoe, and an auxiliary shoe slidably mounted on said parallel rods for lateral movement relative to the main shoe, said auxiliary shoe being located forwardly of said main shoe.

11. An ironing machine including an ironing roll, a main ironing shoe extending along the major portion of the roll, a structure pivotally connected to the main shoe, said structure including parallel guide means parallel to the axis of the roll, an auxiliary shoe slidably mounted upon said guide means, and latching means for latching said pivotal connection.

12. An ironing machine including an ironing roll, a main ironing shoe extending along the major portion of the roll, a structure pivotally connected to the main shoe, said structure including parallel guide means parallel to the axis of the roll, an auxiliary shoe slidably mounted upon said guide means, and means for yieldingly latching said structure to said main shoe.

13. An ironing machine including an ironing roll, a main ironing shoe extending along the major portion of the roll, a structure resiliently connected to said main shoe, an auxiliary shoe pivotally connected to said structure for cooperation with said roll, and latch means for latching said auxiliary shoe to said structure.

14. An ironing machine including an ironing roll, a main ironing shoe extending along the major portion of the roll, a structure resiliently connected to said main shoe, an auxiliary shoe, a laterally movable mounting for said auxiliary shoe, a pivotal connection connecting said mounting and said structure, and latch means for latching said mounting to said structure.

15. An ironing machine including an ironing roll, a main ironing shoe extending along the major portion of the roll, an auxiliary ironing shoe adapted to cooperate with said roll, an electrical heating circuit for said machine including a first heating circuit portion having extensive heating means in heat exchange relation with an extensive portion of said main shoe, said circuit including a second heating circuit portion having extensive heating means in heat exchange relation with another extensive portion of said main shoe, said circuit including a third heating circuit portion having heating means in heat exchange relation with said auxiliary shoe, and control means having one optional circuit connection connecting said second and third heating circuit portions to said supply source and disconnecting the first circuit portion and a second optional connection connecting said first and second heating circuit portions to said supply source and disconnecting said third circuit portion.

16. An ironing machine including an ironing roll, a main ironing shoe extending along the major portion of the roll, an auxiliary shoe located forwardly of said main shoe, a pivot pin having its axis parallel to the axis of the roll pivotally connecting said main shoe and said auxiliary shoe, and latch means for releasably latching said auxiliary shoe in a first position forwardly of the main shoe and in a second position above the main shoe.

17. An ironing machine including an ironing roll, an ironing shoe adapted to cooperate with said roll, a shoe supporting arm connected to said shoe, a shoe operating shaft, an arm connected to said shaft, an adjustable link and spring connection connecting said arms having two fixed spaced adjustable connected positions providing a short and a long connection, and means for connecting said adjustable link and spring connection into either of said two positions.
